UNITED STATES PATENT OFFICE

172,940

COMPASS OR THE LIKE

Howard S. Taylor, Fox River Grove, Ill., assignor
to Airguide Instrument Company, a corporation
of Illinois

Application March 17, 1954, Serial No. 29,575

Term of patent 14 years

(Cl. D42—7)

To all whom it may concern:

Be it known that I, Howard S. Taylor, a citizen of the United States, residing at Fox River Grove, in the county of McHenry, State of Illinois, have invented a new, original, and ornamental Design for a Compass or the like, of which the following is a specification, reference being had to the accompanying drawings forming a part thereof.

In the drawings:

Fig. 1 is a side elevational view of a compass or the like showing my new design;

Fig. 2 is a top plan view thereof.

The dominant features of the design are shown in full lines.

I claim:

The ornamental design for a compass or the like, as shown and described.
